UNITED STATES PATENT OFFICE.

J. A. SHEFFER, OF ROCHESTER, NEW YORK.

COAL-SIFTER.

Specification of Letters Patent No. 26,789, dated January 10, 1860.

To all whom it may concern:

Be it known that I, J. A. SHEFFER, of the city of Rochester, in the county of Monroe and State of New York, have invented 5 certain new and useful Improvements in Machines for Riddling or Sifting Ashes and Separating the Cinders Therefrom; and I do hereby declare the following to be a full and accurate description thereof, reference 10 being had to the accompanying drawings, making part of this specification, and to the letters of reference marked thereon, the same letters referring to like parts in all the figures.

15 Of said drawings Figure 1 is a perspective view of my improved riddling machine with the cover partially open. Fig. 2 is a side elevation—the side of the outer box being removed; and Fig. 3 is an end elevation—the 20 end of the outer box being removed.

The nature of this invention consists in an improved arrangement and combination of parts whereby the cinders are easily and efficiently separated from the ashes, without 25 any danger of the dust being diffused in the apartment or around the operator; and whereby the dust with which the outer box is filled after operating the riddle is prevented from resettling on the cinders.

30 To attain these objects it is obviously necessary that the riddle receive a reciprocating or shaking motion; that both the riddle and the containing box be closely covered; and that the means of operating the 35 riddle be accessible from the outside.

On referring to the drawings it will be observed that the riddle (B) slides upon ways (W W) attached to the outer box (A) and that by means of these ways it is kept 40 sufficiently close to the cover of said box (A) to require no cover of its own.

Motion is imparted to the riddle by means of the handle (H) partially rotating the rockshaft (R) which carries two slotted 45 arms (a a) which act upon pins (P P) at-

tached to the riddle as shown in Figs. 2 and 3. By means of the open slots in the arms (a a) the riddle moves in the plane of the ways (W W), although the arms themselves have a circular or radial motion; while at the same time the riddle is easily removed for the purpose of emptying its contents. And from the riddles being less than the containing box and thus leaving an open space at either end all the clinkers &c which are found in the cinders can be picked out by raking them over with the handle H and then dropped among the ashes. The handle D serves to prevent the handle H from being pushed too far and thus striking the riddle against the end of the box (A). And there is another handle on the opposite side (not seen in the drawing) to be used with the handle D for lifting or carrying the 60 whole.

It will thus be seen that the various operations of filling the riddle, separating the ashes and cinders and depositing each in its proper place outside the box are all reduced to the utmost simplicity. But one cover has to be removed in order to expose both the riddle and the box; and it is not required to move the whole box and its contents in order to separate the ashes as is the case in most other machines. While all the joints and bearings are susceptible of packing so as to prevent the escape of the smallest 70 quantity of dust.

Having thus described my invention, what I claim therein as new and desire to secure by Letters Patent is—

The combination and arrangement of the rockshaft (H R a a) and ways (W W) with the riddle (B) and containing box (A) in the manner and for the purpose substantially as set forth.

J. A. SHEFFER. [L.S.]
